UNITED STATES PATENT OFFICE.

EDWIN E. SLICK, OF PITTSBURGH, PENNSYLVANIA.

CONVEYER PAN.

Application filed July 24, 1926. Serial No. 124,644.

The present invention relates broadly to lehr conveyers and more particularly to improved pans adapted to be assembled to provide a lehr structure suitable for use with glassware and the like. It will be understood, however, that the utility of the invention is not limited with respect to the particular use to which the structure is put.

It is customary in the art to which the present invention relates to provide lehr conveyers comprising side chains between which extend pans for carrying the articles to be annealed. When the conveyers get beyond a certain width, considerable difficulty is encountered not only in getting a uniform driving action on the different chains due to expansion and contraction thereof, but in preventing the pans from sagging, twisting or warping. When such a sagging or other deformation of the pans occurs, they lose their utility as supporting means due to the tendency of articles carried thereby to topple over and become broken.

The present invention has for one of its objects the provision of a conveyer or lehr pan of improved construction adapted to provide sufficient strength to prevent objectionable deformation thereof, and suitable when used in extremely wide lehrs for the addition thereto of intermediate supporting means.

Other advantages of the present invention arise from the provision of a lehr pan of extreme simplicity and capable of being easily constructed from relatively light gauge material. The weight of the finished pan may accordingly be kept within extremely reasonable limits.

In the accompanying drawings there are shown, for purposes of illustration only, certain preferred embodiments of the present invention, it being understood that the drawings do not define the limits of my invention, as changes in the construction and operation disclosed therein may be made without departing either from the spirit of the present invention or the scope of my broader claims.

In the drawings,
50 Figure 1 is a top plan view partly broken

away, of one form of pan constructed in accordance with the present invention;

Figure 2 is a side elevational view of the pan structure of Figure 1;

Figure 3 is a transverse sectional view on 55 an enlarged scale through the pan of Figures 1 and 2;

Figure 4 is a partial sectional view similar to Figure 3, illustrating another embodiment of the invention;

Figure 5 is a view similar to Figure 3 showing still another form of the invention;

Figure 6 is a side elevational view of the structure of Figure 5;

Figure 7 is a top plan view of a portion 65 of a conveyer constructed as shown in Figures 5 and 6, and

Figure 8 is an end elevational view of the pan of Figure 7.

In carrying out the present invention, 70 there may be constructed a conveyer pan for lehrs comprising a supporting member 2 having edges 3 downturned throughout substantially the full length of the supporting member. Cooperating with the supporting member is a reinforcing member 4 substantially U-shaped in cross section throughout the major portion of its length as clearly shown in Figure 3. The reinforcing member has horizontally projecting side flanges 80 75 giving to the reinforcing member an overall width such that it substantially fills the space between the downturned edges 3. The two members may then be secured together in any desired manner, as by rivets 6 as shown 85 in Figure 3, or by turning the edges 3 inwardly as shown at 3' in Figure 4 to firmly interlock the respective parts.

The reinforcing member adjacent each end thereof has upwardly inclined portions 7 90 free from side flanges, and merging in horizontally extending substantially flat end portions 8. The end portions 8 directly underlie the end portions of the supporting member and may be secured thereto by the fastening means by which the pan is secured to the conveying chains. Such means will ordinarily comprise rivets, bolts or the like passing through the openings 9.

The main body of both the supporting 100

member and the reinforcing member is provided with openings 10 adapted to permit free circulation of the heating medium in the lehr chamber and uniform heating of the parts of each pan structure.

In some cases, as for example where the pans are to be of exceptional length as necessitated by wide lehrs, the pans may each have secured thereto one or more intermediate supporting means such as rollers 11 or the like, shown for example in Figures 5 to 8, both inclusive. Such rollers may conveniently be attached by inverted U-shaped brackets 12 secured to the supporting member 2' and extending downwardly through the reinforcing members 4'. Each bracket may carry a pin 13 extending through the arms of the brackets and forming axles for the rollers.

20 In all cases the supporting members are strengthened by the downturned, or downwardly and inwardly turned, edges 3 or 3' respectively, whereby the main body of the supporting member which constitutes the 25 ware receiving portion thereof is kept substantially flat. The reinforcing members not only give additional strength effective against warping, but also act as guides to prevent sagging of the pans. The comparatively deep sides of the reinforcing members 30 constitute beams which are highly effective relative to the weight of the pans.

Certain advantages of the present invention arise from the provision of pans adapted 35 to withstand comparatively high temperatures, and capable of being easily constructed and assembled.

Other advantages of the invention arise from the provision of pans having their 40 supporting surfaces strengthened against both sagging and against twisting or warping.

Still other advantages of the invention arise from the provision of pans comprising upper supporting members and lower reinforcing members, both of said members 45 preferably having side portions, so shaped as to constitute strengthening means.

I claim:

1. As an article of manufacture, a pan for 50 lehr conveyors, comprising a supporting member having strengthening means effective throughout the major portion of the length thereof, and having reinforcing means secured thereto and spaced therefrom throughout a substantial portion of the 55 length of the pan.

2. As an article of manufacture, a pan for 60 lehr conveyors, comprising a supporting member having strengthening means effective throughout the major portion of the length thereof, and having reinforcing means secured thereto and spaced therefrom throughout a substantial portion of the 65 length of the pan, said reinforcing means comprising a reinforcing member substan-

tially U-shaped in cross section throughout at least a portion of the length thereof.

3. As an article of manufacture, a lehr pan comprising substantially flat end portions adapted for cooperation with conveying chains, an upper intermediate portion having downturned edges, and a lower intermediate portion having upwardly projecting edges secured to the upper portion. 70

4. As an article of manufacture, a lehr 75 pan comprising substantially flat end portions adapted for cooperation with conveying chains, an upper intermediate portion having downturned edges, and a lower intermediate portion having upwardly projecting edges secured to the upper portion, said lower intermediate portion being substantially U-shaped in cross section. 80

5. As an article of manufacture, a lehr 85 pan comprising substantially flat end portions adapted for cooperation with conveying chains, an upper intermediate portion having downturned edges, and a lower intermediate portion having upwardly projecting edges secured to the upper portion, said lower intermediate portion being substantially U-shaped in cross section with laterally projecting edges. 90

6. As an article of manufacture, a lehr 95 pan comprising substantially flat end portions adapted for cooperation with conveying chains, an upper intermediate portion having downturned edges, and a lower intermediate portion having upwardly projecting edges secured to the upper portion, said upper and lower portions having the main body portions thereof spaced throughout the major portion of the length of the pan. 100

7. As an article of manufacture, a lehr 105 pan comprising substantially flat end portions adapted for cooperation with conveying chains, an upper intermediate portion having downturned edges, and a lower intermediate portion having upwardly projecting edges secured to the upper portion, said upper and lower portions having the main body portions thereof spaced throughout a substantial portion of the length of the pan. 110

8. As an article of manufacture, a pan 115 for lehr conveyors, comprising a supporting member having strengthening means effective throughout the major portion of the length thereof, and having reinforcing means secured thereto and spaced therefrom throughout a substantial portion of the 120 length of the pan, said pan being provided with a supporting roller at an intermediate portion thereof.

9. As an article of manufacture, a pan for 125 lehr conveyors, comprising a supporting member and a reinforcing member below and spaced from the supporting member, said supporting member having end portions shaped for cooperation with conveying chains. 130

10. As an article of manufacture, a pan
for lehr conveyers formed of a hollow body
having its upper face serving as a support- 10
ing member and its lower part as a reinforcing
member, said supporting member having
5 end portions shaped for cooperation with
conveying chains.

11. As an article of manufacture, a pan

for lehr conveyers formed of a hollow body
having its upper face serving as a support- 10
ing member and its lower part as a reinforcing
member, and ventilating holes opening
from the interior of the hollow body.

In testimony whereof I have hereunto set
my hand.

EDWIN E. SLICK.
